CLAMP FOR STRINGING RACKETS

Filed Nov. 17, 1949

Patented Sept. 2, 1952

2,608,737

String holding arm of racket stringing apparatus, the jaws of which are normally separated and held in that position by a camming device, which device is operable to force the jaws together to grip the string when tension is applied thereto, and to release the grip when tension is removed, the jaws being held in the separated position by a spring, the camming device being a lever having a cam surface which is urged into engagement with the jaws to force them together, and the lever being held in the released position by a camming washer which is urged into engagement with the lever to hold it in the released position.

This invention relates to improvements in racket stringing apparatus, and more particularly to improvements in the string holding arm of such apparatus.

UNITED STATES PATENT OFFICE

2,608,737

CLAMP FOR STRINGING RACKETS

Edmundo H. Serrano, St. Louis, Mo.

Application November 17, 1949, Serial No. 127,804

2 Claims. (Cl. 24—250)

1

This invention relates to certain new and useful improvements in racket stringing apparatus.

The primary object of the invention is to provide racket stringing apparatus which is a special improvement upon that shown in my prior Patents Nos. 2,188,250, dated January 23, 1940, or 2,154,870, dated April 18, 1939, and more especially in the string tensioning device and string clamping or gripping means of the string holding arm thereof so as to prevent breaking of the string when tension is placed thereon during the stringing of the racket.

It is also an object of the invention to provide a novel string holding arm having normally expanded or separated jaws with heads designed to receive and grip the string therebetween or permit wrapping or winding of the string thereon and gripping thereof between the jaws when forced together so that the string does not take any abrupt angles or bends and may without injury thereto be safely placed under the desired tension during the stringing operation in proper line with the holes of the racket string frame so that breaking or parting of the string is guarded against, together with a manually-actuated cam lever means for forcing the jaws of the puller arm into string gripping or clamping relation or for releasing the same for movement automatically to normally expanded or separated position for further threading of the string through the holes of the racket string frame for completion of the stringing of the racket.

A further object of the invention is to provide a novel string holding arm for mounting on the sliding tension bar of the string tensioning device, which holding arm comprises coacting gripping jaws each with semi-ovate string gripping heads with flat inner surfaces between which a section or length of the string is clamped and held under tension after the string is horizontally wrapped about the heads in external string-receiving grooves therein to eliminate abrupt bends in the string and avoid the necessity of using a rubber or other cushion band about the heads or drum in order to firmly clamp and hold or anchor the string thereto when under tension during the stringing of the racket, and the requirement of frequent replacement of such rubber band in order to effectively clamp or anchor the string to the holding arm.

A still further and important object is to provide simple and novel cam means for forcing the sections or jaws of the movable split holding arm together or for releasing the camming action whereby the jaws will separate to release the grip on the string, said means including a forked

lever straddling the normally expanded sections of the holding arm and a connection through the arm between the arms of the lever having coacting cam surfaces and washers for effecting the gripping and releasing action of the jaws of the holding arm.

With the above and other objects in view that will become apparent as the nature of the invention is better understood, the same consists in the novel form, combination and arrangement of parts hereinafter more fully described, shown in the accompanying drawings, and claimed.

In the drawing:

Figure 1 is a fragmentary perspective view showing a portion of the racket frame and the improved holding arm of the racket stringing apparatus of my prior patent with a section of the gut string extending therebetween gripped or clamped and held under tension;

Figure 2 is an enlarged fragmentary inside elevation of the string holding arm with the jaws in released position;

Figure 3 is a view similar to Figure 2 with the jaws in clamping position;

Figure 4 is an enlarged fragmentary vertical sectional view taken on line 4—4 of Figure 1;

Figure 5 is a fragmentary perspective detail view of one end of the squared bolt or shaft of the jaw-actuating cam means of the holding arm;

Figure 6 is a fragmentary detail of an attaching end of the forked cam actuating lever of the holding arm jaws, and

Figure 7 is a detail face view of one of the camming washers.

Referring more in detail to the accompanying drawing, the racket stringing apparatus to which the present improvement is applied, is of the type shown in my prior Patents Nos. 2,188,250, dated January 23, 1940, or 2,154,870, dated April 18, 1939, hereinbefore referred to, in which the string frame 10 of the racket is held in clamps or jaws at the throat and nose portions of the apparatus in the manner shown in the patent with the string 11 extending through the staggered or otherwise arranged holes 12 through the frame.

The bar or rod 13 of the rectangular cross-section as shown, corresponds to the laterally offset end 31 of the rod 29 of said Patent 2,188,250, which slidably moves in the anti-friction bearings of the housings 28 at diametrically opposite sides of the upper end of the tubular post 10 to cause movement of the arm 32 of the patent carrying the string gripping drum for placing the string under tension.

However, in the present embodiment, the string holding arm is designated generally at 14, the

same being split or bifurcated and rigidly supported in an upstanding position through the medium of a rectangular sleeve 15 at the lower end of the arm 14 fitting and anchored in any suitable way on the bar or rod 13. The holding arm 14 comprises a split member including a pair of upstanding sections or plates 16 and 17 constituting the split arm 14. The section 16 is rigid or formed integral with the sleeve 15 at one side of the transverse center thereof to form an upwardly facing shoulder 18 at the top of the other side of the sleeve, which is serrated as at 19 to provide spaced fingers 20 all centrally apertured horizontally in register to receive a pivot pin 21. The section 17 is formed with a thick flat lower end 22 disposed above the shoulder 18 and is likewise serrated as at 23 to provide spaced fingers 24 in staggered relation to serrations 19 and fingers 20 so that the opposite fingers extend into the opposed serrations. Fingers 24 are likewise apertured, the same as the fingers 20, to also receive the pivot pin 21 to pivotally mount the section 17 on the sleeve 15 for lateral movement toward and away from the section 16. However, it is to be understood that any other suitable pivot arrangement or mounting of the section 17 may be provided to permit separation and contraction of the sections or jaws 16 and 17 relative to each other on the sleeve 15 limited at the pivot and shoulders.

The opposed inner faces of sections 16 and 17 of the holding arm 14 are flat as at 25, the lower portion of the sections being curved inwardly or forwardly as shown and the upper portions extending upright and preferably widened and formed with enlarged substantially semi-circular or semi-ovate heads or jaws 26 projecting laterally outwardly of the outer sides of the holding arm sections as clearly seen in Figures 1, 2, 3 and 4 of the drawings. A coil spring 27 is interposed between clamp sections or plates 16 and 17 to effect normal separation thereof for releasing the engagement between the clamp sections or plates at the heads or jaws 26 and the string 11 therebetween, and said spring may be seated at its ends in opposed seats or recesses 28 in the inner sides of the upright upper portions of the sections to prevent displacement of the spring, while still permitting contraction of the puller arm sections in moving the same together to clamp the string between the jaws.

The enlarged heads or jaws 26 are likewise flat at their inner faces at 29 flush with the flat faces 25 of the arm sections 16 and 17, and are convex on the outside as at 30 with horizontally aligned intermediate concaved grooves 31 on the outside or periphery to receive the spring 11 when coil-wound or looped thereon against displacement. The forward or inner portions or corners of the jaws or heads 26 are convexly rounded as at 32 so as to converge inwardly toward the flat faces 29 or diverge outwardly away from the same to provide a smooth entrant opening for the string and prevent injury to the string by sharp corners but the exit or outer corners 33 are in alignment and may be sharp as shown since the string is not bent around these corners but across the smooth surface provided across the arms when wound on the heads or jaws and passes outwardly from between the flat faces 29 at this point, at its free end. It should be noted that the two cooperating heads or jaws form a substantially heart-shaped member together and that the string 11 may be simply extended between the flat inner faces of the jaws for lighter tensions thereon in stringing a racket frame, or

may by adjusting the bar or rod 13 and arm 14 in the proper position with relation to the holes 12 in the string frame 10 of the racket when tension is to be applied as shown in Figure 1, be extended at the outer side of one jaw 26 and looped around the jaws in the grooves 31 so as to pass evenly across the corners 33 on the aligned convex peripheries or surfaces 30 at this point, and then around the surface 30 of the other jaw and enter between the jaws around the convexly rounded corner 32 thereof to pass between the flat inner faces 29 to be clamped and held when the jaws are contracted into gripping or clamping relation as will be hereinafter explained.

The sections 16 and 17 may be centrally ribbed lengthwise on the outside for strength as at 34 merging into the sleeve 15 and thick lower end 22, respectively, at the bottom and formed at the upper angle bends or curves therein adjacent their upright upper portions with circular bosses 35 having horizontal concavities 36 in their outer faces and circular aligned bores 37 are provided through the sections or plates 16 and 17 opening centrally through the concavities 36. A polygonal or squared bolt or shaft 38 extends through the bores 37 to freely turn therein and projects outwardly at its ends which are threaded at one or both ends as at 39. Diametrically concavo-convex cams, camming washers or plates 40 with polygonal or squared central apertures 41 conforming to the cross-section of the bolt or shaft 38, are mounted on the extending ends of the latter to turn therewith and slide thereon with their convex inner faces seating in the concavities 36 and conform thereto in the normally separated or expanded positions of the sections and jaws as seen in Figures 2 and 4 of the drawings. A forked or bifurcated lever 42 with a ball or other hand or finger grip 43 at its face end has its divergent sides or arms straddling the sections of the puller arm 14 and camming washers 40, being formed with circular bearing portions 44 at the ends of the sides or arms each with central polygonal or square openings 45 fitting on an end portion of the squared bolt or shaft 38 against the concaved outer faces of the camming plates or washers 40 and held by a head or nut 46 fixed or upset on one end such as a threaded end 39 and a pair of nuts 47 screwed on the other threaded end 39, which in the instance shown, is slightly longer than the first referred to threaded end. By this means or otherwise as desired, the arms of the lever are held firmly against the washers and the lever and washers fixed to the bolt to turn together positively.

In the normal expanded or release position of the jaws as seen in Figures 2 and 4, the handle or lever 42 is lowered or swung down against the arm 14 and after the string is drawn between the jaws directly or wrapped, looped or wound around the heads or jaws 26 in the grooves 31 and the end pulled between the jaws, the lever 42 is raised to the position shown in Figures 1 and 3 to turn the bolt or shaft and with it the camming washers or plates 40 from their conforming positions diametrically in the concavities 36 to dispose the diametrical convexities or high points of the washers substantially at right angles to their first position transversely to the concavities 36 to force the sections 16 and 17 and jaws 26 thereof together to tightly clamp or anchor the string under tension for stretching and stringing the socket frame substantially in the manner described in my prior patents referred to above. Release of the string is of course effected merely

by swinging the lever or handle downwardly to permit the separation of the jaws under the action of the spring 27 as previously explained. The racket stringing apparatus is of course of the type wherein a string tensioning device is adapted to have a string coiled therearound and held or clamped by the gripping jaws to exert a holding force on a string threaded through a tennis, squash or badminton frame and to be ineffective during continued movement after the string has received the desired tension, and wherein a tensioned portion of the string is held under tension while the tensioning device is being engaged with another portion of the string and wherein means is provided for holding the tension against movement, and, also, wherein a racket supporting head is mounted upon the upper end of a standard and wherein the string is tensioned by sections with a tensioned string section held under tension while tensioning another section, whereby with proper adjustment of the string tensioning means any racket frame may be properly and efficiently strung.

While there is herein shown and described the preferred embodiment of the invention, it is nevertheless to be understood that minor changes may be made therein without departing from the spirit and scope of the invention as claimed.

I claim:

1. In a string holding means for a racket stringing apparatus, string tensioning means including a string holding arm supported for tensioning and releasing movements, said arm including a rigid section and a pivoted section movable toward and away from the rigid section, enlarged outwardly projecting semi-ovate jaw heads on the upper ends of the sections having horizontally grooved outer peripheries and flat substantially parallel inner faces, the inner corners of the heads being convexly rounded and the outer corners in alignment for winding a string thereon and between said faces, a shaft extending through the sections for rotation, said sections having outer cam surfaces, cam plates mounted on the shaft against the cam surfaces to turn with the shaft, a forked lever having bearing ends fixedly mounted on the shaft against the cam plates to turn the shaft and cam plates to force the latter inwardly against the cam surfaces for contracting the sections and jaw heads in gripping relation to a string and to release the same, and means to separate the sections and jaws.

2. In a string holding means for a racket stringing apparatus, string tensioning means including a string holding arm supported for tensioning and releasing movements, said arm including a rigid section and a pivoted section movable toward and away from the rigid section, enlarged equal sized outwardly projecting semi-ovate jaw heads on the upper ends of the sections having horizontally grooved outer peripheries and flat substantially parallel inner faces, the inner corners of the heads being convexly rounded and the outer corners in alignment for winding a string thereon and between said faces, a shaft extending through the sections for rotation, said sections having diametrically concaved outer camming recesses at their outer sides, diametrically concavo-convex cam washers having their convex faces fitting said recesses, a polygonal bolt extending through aligned circular bores through the sections centrally of the camming recesses with the washers fixed thereon outwardly of the recesses to turn therewith and slide thereon, a forked lever having ends fixed on the bolt to turn therewith outwardly of and against the washers to force the jaw heads and sections in contracted relation in one position of the lever to grip the string and release the same for expansion and separation in another position, and a spring between the sections to normally separate the same and jaw heads.
